EDGE SETTING AND INDENTING MACHINE.

1,125,894.

Specification of Letters Patent. Patented Jan. 19, 1915.

Application filed January 10, 1914. Serial No. 811,470.

To all whom it may concern:

Be it known that I, ZOTIQUE BEAUDRY, a citizen of the United States, residing at Lynn, in the county of Essex and State of Massachusetts, have invented new and useful Improvements in Edge Setting and Indenting Machines, of which the following is a specification.

This invention relates to a machine for setting and indenting the edges of the soles of boots and shoes.

The object of the invention is to provide a machine of the character set forth which will operate to set or burnish the edge of the sole of a boot or shoe and at the same time will indent the upper edge portion of said sole.

In the machine of this invention a rotary edge setting tool is employed for setting the edge of the sole and in combination therewith a rotary indenting tool is utilized for indenting the upper edge portion of said sole, the indenting tool being free to rotate relatively to the edge setting tool so that while the edge setting tool is rapidly and positively rotated by suitable means, the indenting tool rotates only to the extent that it may be rotated by the movement of the edge of the sole of the shoe in contact therewith. Said indenting tool is preferably, although not necessarily, arranged slightly eccentric to the edge setting tool and in its preferred form has a shank attached thereto which is adapted to rotate in an eccentric bearing provided in the shaft to which the edge setting tool is fastened, so that the indenting tool can rotate and also have imparted thereto a rapid movement transversely of the shaft upon which it is mounted. Thus the indentations in the sole made by the indenting tool are rendered much more distinct and perfect, due to this transverse movement of the tool than would be the case if the indenting tool simply had a rotary motion imparted thereto. In other words, the corrugations of the indenting tool may be given a movement transversely of the shaft upon which the tool is mounted, which results in a rubbing motion of the corrugations of the indenting tool longitudinally of said corrugations, and transversely of the sole of the shoe. It is also desirable, in some instances, to impart a reciprocating motion to the indenting tool longitudinally of the shaft upon which it is

mounted or laterally of the indenting tool itself and of the sole against which the corrugations of the indenting tool bear, and my invention contemplates the employment of means whereby a lateral movement may be imparted to the indenting tool as well as a movement of said indenting tool transversely of the sole or of the shaft upon which it is mounted.

While I have illustrated my invention as embodying an indenting tool which has means for imparting a movement thereto transversely of the sole and of the shaft upon which it is mounted, I do not wish to be understood as limiting my invention to this specific embodiment thereof, as the indenting tool may be mounted concentric with the edge setting tool without departing from the spirit of my invention. I believe it to be new, however, to combine a rotary edge setting tool with a rotary indenting tool, the rotary indenting tool being free to rotate relatively to the edge setting tool and the edge setting tool having means whereby the same may be positively and rapidly rotated.

The invention consists in the combination and arrangement of parts set forth in the following specification and particularly pointed out in the claims thereof.

85

Referring to the drawings: Figure 1 is a front elevation of a portion of an edge setting machine embodying my invention and having shown in connection therewith a portion of a shoe in section in position to be operated upon. Fig. 2 is a front elevation of the same. Fig. 3 is a sectional elevation taken on line 3—3 of Fig. 2. Fig. 4 is a detail section taken on line 4—4 of Fig. 1. Fig. 5 is a front elevation of a modified form of my invention showing the same as applied to a different form of edge setting machine and showing a portion of a shoe in section in connection therewith and in position to be operated upon.

100

Like numerals refer to like parts throughout the several views of the drawings.

In the drawings, referring to Figs. 1 to 4 inclusive, 10 is the frame of the machine in which is journaled a shaft 11. Said shaft is rotated by a pulley 12 driven by a belt 13 and rotates in suitable bearings 14 and 15 in the frame of the machine. A rotary edge setting tool 16 is fastened to one end of the shaft 11 and in the operation of the

105

110

machine is rapidly rotated to burnish or set the edge of the sole of the shoe which is held thereagainst by the operator in a manner well known to those skilled in this art.

5 The shaft 11 has a bore 17 therein which is eccentric thereto, and within this bore is rotatably mounted a spindle 18, to the outer end of which is fastened a rotary indenting tool 19, said indenting tool being held 10 firmly on the spindle 18 by a screw 20 and washer 21, said screw having screw-threaded engagement with the spindle 18, and thus holding the indenting tool 19 firmly pressed against a shoulder 22 formed 15 on the spindle 18.

The indenting tool 19 is provided around its periphery with sharp edged teeth or corrugations 23 which are adapted to form serrations or indentations upon the upper edge of 20 the sole of the shoe when the same is pressed thereagainst. It will be noted that the indenting tool 19 is free to rotate independently of the shaft 11 and in operation the outer edge of the sole 24 of the shoe 25 is held in contact with the portion 26 of the edge setting tool 16, while the upper edge portion 27 of the sole bears against the corrugations 23 on the indenting tool 19.

An arm 27 bears against the head of the 30 screw 20 and prevents the indenting tool and its spindle from moving longitudinally of the shaft except to a slight extent, as, for example, where a slight difference in thickness of the sole occurs, in which case 35 the arm 27 is capable of yielding slightly to allow for such variation, it being noted that the arm 27 is curved slightly and is somewhat resilient. The arm 27 is adjustably fastened by means of a set-screw 28 40 to a bracket 29 which is fastened to the frame 10 of the machine.

In order to hold the upper edge portion 45 of the sole 24 firmly and still yieldingly against the corrugated portion of the indenting tool 19, a presser foot 30 is provided. This presser foot is adapted to slide upon a stem 31 which is adjustably fastened by a set-screw 32 to a bracket 33 which, in turn, is fastened to the frame of the machine. The distance to which the presser foot 30 can slide in one direction on the stem 31 is limited by a shoulder 34 on said stem and in the opposite direction the distance to which said presser foot can slide is 50 limited by a collar 35 fast to said presser foot and adapted to abut against a stop 36 having screw threaded engagement with a pin 37 which is fastened to a collar 38, the collar 38 being fastened to the stem 31 by 55 a set-screw 39.

A spring 40, under compression, is interposed between the collar 38 and the collar 35, thus tending to move the presser foot at all times toward the shoe and to hold 60 the collar 35 against the stop nut 36. When

properly set in relation to the other parts of the machine, the face of the presser foot 30 which bears against the tread of the sole should be in such a position that it will be necessary to compress the spring 40 and 70 move the collar 35 away from the stop nut 36 when the sole of the shoe is placed in the position illustrated in Fig. 1 in readiness to be operated upon by the machine.

The general operation of the mechanism 75 hereinbefore described and illustrated in Figs. 1 to 4 inclusive is as follows: The operator holds the shoe with the outer edge of the sole bearing against the portion 26 of the edge setting tool 16 and with the 80 upper edge portion of the sole 24 bearing against the corrugations 23 on the beading tool 19, said sole being held in this position firmly and yieldingly by the presser foot 30 with its coacting spring 40. The edge 85 setting tool 16 is rotated rapidly by the shaft 11 and burnishes or sets the edge of the sole while at the same time the operator turns the shoe into different positions to bring all of the portions of the edge of the 90 fore part of the sole in contact with the periphery of the rapidly rotating edge setting tool 16. While thus moving the sole into different positions the indenting tool 95 will be rotated by frictional contact with the upper edge portion of the sole and at the same time a rapid movement will be imparted to said indenting tool transversely of the shaft by reason of its being eccentrically mounted on said shaft and thus the 100 corrugations 23 of the indenting tool will impress upon the upper edge portion of the sole a series of indentations, due to the combined rotation of said indenting tool and the transverse movement thereof with relation to the shaft. Thus it will be seen that 105 not only is a rotary motion imparted to the indenting tool, but a reciprocatory movement transversely of said shaft is also imparted thereto, whereby a rubbing action 110 takes place between the corrugations 23 and the leather with which they are in contact, said rubbing movement being in a direction longitudinally of said corrugations and transversely of said shaft and thus the 115 indentations upon the upper edge of the sole are distinctly and permanently produced.

In Fig. 5 a modified form of my invention is illustrated in which the invention is embodied in a machine wherein the shoe 120 is held upon a jack and the edge setting mechanism is moved around the shoe, the frame of said machine being suspended in such a manner as to allow the edge burnishing tool and the indenting tool to be moved 125 backwardly and forwardly around the sole of the shoe while the shoe is supported upon a jack and tipped thereon to coat with the mechanism in enabling the edge burnishing and indenting tool to be brought into con- 130

tact with all portions of the edge of the fore part of the sole of the shoe.

Referring now to Fig. 5, 41 is the rotary edge setting tool and 42 the indenting tool, said indenting tool being mounted to rotate freely with a spindle 43 to which said indenting tool is fastened and which is eccentrically mounted within the shaft 50. The shaft 50 is mounted in a suitable bearing 54 in the frame 46 of the machine and is rotated by means of a pulley 51. The spindle 43 is free to move to a slight extent longitudinally thereof in the shaft 50 and a longitudinal movement is imparted to said spindle 43 and the indenting tool 42 fast thereto by a collar 52 which has an inclined or cam-shaped surface 55 thereon which bears against a similarly inclined or cam shaped surface 56 on the end of the shaft 50, so that as the shaft 50 is rotated a reciprocatory motion will be imparted to the spindle 43 and to the indenting tool 42, the spindle being moved toward the right (Fig. 5) by reason of the inclined surfaces 55 and 56 on the collar 52 and shaft 50 respectively and said spindle being moved toward the left when released by the rotation of the shaft 50 relatively to the collar 52 by the resilient nature of the leather which forms the sole 24 which, slightly expanding when released from extreme pressure, causes the indenting tool 42 to move toward the left as soon as the inclined surfaces 55 and 56 assume positions relatively to each other which allow of such movement. A presser foot arm 44 is pivoted at 45 to the frame 46 and is held by a spring 47 under compression against the tread of the sole 24. Said spring encircles a rod 48 fast to the frame 46 and bears at one end thereof against a collar 49 adjustably fastened to the rod 48, while the other end of said spring bears against the arm 44, whereby said arm is held at its outer end against the tread of the sole 24 of the shoe and thus presses the sole of the shoe against the corrugations of the indenting tool 42.

The operation of this embodiment of my invention is as follows; The shoe is placed upon a jack (not shown in the drawings, but well known to those skilled in the art) and the edge setting tool and indenting tool brought into contact with the edge of the sole 24. Then by a combined tipping of the shoe upon the jack and a swinging movement of the frame 46 the edge setting tool and indenting tool are carried around the edge of the fore part of the sole of the shoe and the sole is thoroughly burnished and indented. During this operation the indenting tool is rotated. It is also given a reciprocatory movement laterally thereof and a reciprocatory movement transversely of the spindle to which it is fastened.

65 While I have described the embodiment

of my invention illustrated in Fig. 5 as applied to a machine in which a jack is employed, it is evident that this embodiment of my invention may be used equally well in a machine of the character hereinbefore described and illustrated in Figs. 1 to 4 inclusive.

I also want it to be distinctly understood that the indenting tool hereinbefore described may be used concentric with the edge setting tool, it may be used eccentric to the edge setting tool or it may be given a movement longitudinally of the shaft to which the edge setting tool is fastened.

Having thus described my invention what I claim and desire by Letters Patent to secure is:

1. A machine for setting and indenting the edge of the sole of a shoe having, in combination, an edge setting tool adapted to engage the outer edge of said sole, means to rotate the same and an indenting tool adapted to engage the upper edge of said sole and rotatable relatively to said edge setting tool.

2. A machine for setting and indenting the edge of the sole of a shoe having, in combination, an edge setting tool adapted to engage the outer edge of said sole, means to rotate the same, an indenting tool adapted to engage the upper edge of said sole and rotatable relatively to said edge setting tool and means adapted to impart a lateral movement to said indenting tool.

3. A machine for setting and indenting the edge of the sole of a shoe having, in combination, an edge setting tool adapted to engage the outer edge of said sole, means to rotate the same, an indenting tool adapted to engage the upper edge of said sole and rotatable relatively to said edge setting tool, means adapted to move said indenting tool laterally thereof and means adapted to move said indenting tool transversely of said edge setting tool.

4. A machine for setting and indenting the edge of the sole of a shoe having, in combination, a rotary shaft, an edge setting tool fast thereto and an indenting tool adapted to engage the upper edge portion of said sole, said indenting tool being eccentrically mounted with respect to said shaft.

5. A machine for setting and indenting the edge of the sole of a shoe having, in combination, a rotary shaft, an edge setting tool fast thereto and an indenting tool adapted to engage the upper edge portion of said sole, said indenting tool being eccentrically mounted with respect to said shaft and free to rotate relatively to said shaft.

6. A machine for setting and indenting the edge of the sole of a shoe having, in combination, a rotary shaft, an edge setting tool fast thereto, an indenting tool adapted to engage the upper edge portion of said

sole, said indenting tool being eccentrically mounted with respect to said shaft and free to rotate relatively to said shaft, and yielding means adapted to bear against the tread of the sole of said shoe, whereby said sole is forced against said indenting tool.

7. A machine for setting and indenting the edge of the sole of a shoe having, in combination, an edge setting tool, means to impart a rotary motion thereto, a rotary indenting tool adapted to engage the upper edge portion of said sole and means adapted to impart a motion to said indenting tool transversely of said edge setting tool.

15 8. A machine for setting and indenting the edge of the sole of a shoe having, in combination, an edge setting tool, means to impart a rotary motion thereto, a rotary indenting tool adapted to engage the upper edge portion of said sole, means adapted to impart a motion to said indenting tool transversely of said edge setting tool and yielding means adapted to bear against the tread of the sole of said shoe, whereby said sole is forced against said indenting tool.

20 9. A machine for setting and indenting the edge of the sole of a shoe having, in combination, a rotary shaft, an edge setting tool fast thereto, a spindle mounted to rotate in a bore provided in said shaft and eccentric thereto and an indenting tool fast to said spindle and adapted to engage the upper edge portion of said sole.

25 10. A machine for setting and indenting the edge of the sole of a shoe having, in combination, a rotary shaft, an edge setting tool fast thereto, a spindle mounted to rotate in a bore provided in said shaft and

eccentric thereto, an indenting tool fast to said spindle and adapted to engage the upper edge portion of said sole and means adapted to move said spindle and indenting tool longitudinally of said shaft.

11. A machine for setting and indenting the edge of the sole of a shoe having, in combination, a rotary shaft, an edge setting tool fast thereto, a spindle mounted to rotate in a bore provided in said shaft and eccentric thereto, an indenting tool fast to said spindle and adapted to engage the upper edge portion of said sole, yielding means adapted to bear against the tread of the sole of said shoe, whereby said sole is forced against said indenting tool and means adapted to move said spindle longitudinally within said bore.

12. A machine for setting and indenting the edge of the sole of a shoe having, in combination, a rotary shaft, an edge setting tool fast thereto, a spindle mounted to rotate in a bore provided in said shaft, an indenting tool fast to said spindle and adapted to engage the upper edge of said sole and a collar on said spindle adapted to engage the end of said shaft, the engaging surfaces of said collar and shaft being cam-shaped, whereby a reciprocatory motion may be imparted to said spindle and indenting tool longitudinally of said shaft.

In testimony whereof I have hereunto set my hand in presence of two subscribing witnesses.

ZOTIQUE BEAUDRY.
